OILING SYSTEM

Fred G. Ellers, Mooreland, Okla.

Application July 2, 1937, Serial No. 151,585
Renewed October 7, 1939

1 Claim. (Cl. 123—196)

This invention relates to improvements in oiling systems for internal combustion engines.

It has been proven in actual tests that approximately fifty per cent of the wear on the pistons and cylinder walls of an internal combustion engine such as used in automobiles occurs during the first five minutes the engine is run after having been idle for three hours or more. The reason for this is that when a warm engine is stopped the lubricating oil drains down from the pistons and cylinder walls leaving them dry and then when the engine is again started it requires some time for the oil to work back up again leaving the parts during this time without the protection of the necessary lubricant.

With the foregoing facts in mind it is the main object of my invention to provide what might be termed an automatic overhead oiling system which will automatically supply a predetermined amount of oil directly atop the pistons each time the motor is started after cooling off and which will thus furnish lubricant sufficient to prevent undue wear until such time as the oil from the usual oiling system works up to the pistons in normal manner.

Another object is to provide an apparatus or device for this purpose in a simple and practical form including a housing having two oil chambers, one connected to the oil line and one to the intake manifold of the engine and with the passage between controlled by a valve which is connected to a thermostat located in communication with either the cooling system or exhaust manifold of the engine in such manner that when the engine is warm the passage will be shut off but when the motor is cool the passage will open and the oil will run to the intake manifold there to be drawn into the engine when it is started.

With these and other objects in view the invention resides in the novel construction and arrangement of parts as hereinafter fully set forth and claimed, reference being had to the accompanying drawing as showing a preferred embodiment of my invention for purposes of exemplification.

In the drawing:

Figure 1 is a side elevation of a conventional type of engine with my oiling system in use thereon.

Figure 2 is an enlarged cross section of my apparatus alone.

In carrying out my invention I provide a housing shown generally at 1 comprising a main section, casing or body 2, a bottom well or cup 3 and an upper cap or head 4. The casing 2 is cylin-

drical in form with the open flanged upper end 5 and the diametrically enlarged and flanged lower end 6 and with the intermediate closed wall or bottom 7. The well 3 is flanged at its upper end 8 and secured by screws 9 to the bottom 6 of the casing 2 and from that point tapers downwardly to terminate finally in the tapped nipple 10. In this manner a well chamber or thermostat chamber 11 is formed below the wall 7 and a conventional form of disk or bulb thermostat is located therein, the margins of the thermostat being anchored between the adjacent flanged ends of the casing 2 and well 3.

The head 4 is flanged at its lower end 12 and is secured by screws 13 to the upper end 5 of the casing 2. This head also has a central or axial tapped bore 14 in alignment with the vertical axis of the unit as a whole and has a radially extended inlet passage 15 leading out through one side. A large screw 16 is threaded into the upper end of the bore 14 above the level of the passage 15 and below the same a valve bushing 17 is screwed in the bore, the said bushing having the central port 18 flared into a seat 19 at its lower portion.

The wall 7 has a central bore 20 for the reception of a valve push rod 21 which is secured at 22 to the upper shell of the thermostat T and is threaded at 23 at its upper end. A needle valve 24 is screwed on this upper end of the push rod 21 and is thus lined up so that its tapered end 25 will enter the valve seat 19 of the bushing 17 when the thermostat expands or swells and will thus close off communication with the casing 2 through the bore 14. An inverted cup-shaped hood 26 is secured to the valve push rod 21 below the valve 24 by nuts 27 screwed on the rod.

The wall 7 which forms the bottom of the lower or outlet oil chamber 28 within the casing 2 is of rounded formation as shown at 29 with an upwardly sweeping central boss 30 around the upper opening of the bore 20 and the hood 26 hanging over this boss will prevent oil from running down through the bore as will be understood.

An outlet passage 31 leads from the lowest point of the chamber 28 out radially through the wall of the casing 2 and both this passage and the aforesaid inlet passage 15 are tapped at their outer ends as at 32 for the reception of conventional couplings 33.

In use the unit is mounted and connected to the engine E by a pipe 34 which is screwed into the nipple 10 and into the water jacketed cylinder head C so that the water from the cooling

system enters the well chamber 11. In lieu of this the pipe 34 may lead to the exhaust manifold (not shown). A line or tube 35 is then led from the inlet passage 15 to the oil line L feeding the usual oil gauge G (or to any other part of the oiling system) and another line 36 is led from the outlet passage 31 to the intake manifold M. Then oil will enter the passage 15 and flow into the bore 14 filling the same. The oil flow may be controlled by a metering pin valve 37 of usual form and the volume of the bore may be varied by screwing the screw 16 in or out as required. The engine being cold the water in the chamber 11 is cold and the thermostat T is in a contracted condition so that the needle valve 24 is pulled out of its seat 19 as shown in Figure 2. The oil will then run into the chamber 28 and out through the passage 31 and line 36 into the manifold M. As soon now as the engine is started this oil will be drawn into the tops of the cylinders and will lubricate the same until the usual engine oiling system takes up its work. As soon as the water in the well chamber 11 warms up then the thermostat T will expand closing the valve 24 and sealing the bore 14 so that a quantity of oil will fill the same ready for the next operation. This valve 24 will remain closed until the engine again

cools off and it will be evident therefore that the action is entirely automatic. The screw 16 permits adjustment of the amount of oil to suit any number of cylinders and the metering pin valve 37 allows control of the rate of flow as may be required.

While I have herein set forth a certain preferred embodiment of my invention it is understood that I may vary from the same in minor structural details so as best to provide a practical device for the purposes intended, not departing from the spirit of the invention and within the scope of the appended claim.

I claim:

In combination with an engine including an oil line, an intake manifold, a housing having a bore with an inlet connected to the oil line, a valve operating adjacent the bore, the said housing having an oil chamber communicating with the bore when the valve is open and having also a well connected to the engine whereby heat from the engine will enter the well, a thermostat in the well and connected to the said valve, a line connecting the said oil chamber to the intake manifold of the engine, and means for varying the volume of the said bore.

FRED G. EILERS.
